UNITED STATES PATENT OFFICE

153,182

DESIGN FOR A COMBINED SCREWDRIVER
AND INERTIA WEIGHTSydney Skamser, Los Angeles, Calif., assignor to
Skamser Spindriver Corporation of America,
Long Beach, Calif., a corporation of California

Application December 9, 1946, Serial No. 135,354

Term of patent 14 years

(Cl. D54—13)

To all whom it may concern:

Be it known that I, Sydney Skamser, a citizen of the United States, residing at Los Angeles, in the county of Los Angeles and State of California, have invented a new, original, and ornamental Design for a Combined Screwdriver and Inertia Weight, of which the following is a specification, reference being had to the accompanying drawing, forming a part thereof.

Fig. 1 of the drawing is a perspective view of a combined screwdriver and inertia weight, embodying my new design and showing the inertia weight for the screwdriver at the top of the screwdriver shank;

Fig. 2 is a perspective view of the article of Fig. 1 and also showing the inertia weight at the top of the screwdriver shank, but showing it from a different angle than that of Fig. 1; and

Fig. 3 is a front view of the article of Figs. 1 and 2, but showing the inertia weight thereof disposed at the bottom of the screwdriver shank,

the inertia weight being slidable on the screwdriver shank.

I claim:

The ornamental design for a combined screwdriver and inertia weight, as shown and described.

SYDNEY SKAMSER.
